FACIAL MUSCLE EXERCISER

Ralph E. Welch, 917 Winthorne Drive, Apt. D-26,
Nashville, Tenn. 37217

Filed Aug. 24, 1973, Ser. No. 391,060

Term of patent 14 years

Int. Cl. D21—02

U.S. Cl. D83—1 T

FIG. 1

FIG. 2

FIG. 3

FIG. 4

FIG. 1 is a perspective view of a facial muscle exerciser according to the invention;

FIG. 2 is a side elevation thereof;

FIG. 3 is a plan view thereof; and

FIG. 4 is a front elevation thereof.

I claim:

The ornamental design for a facial muscle exerciser, as shown.
